UNITED STATES PATENT OFFICE.

WILLIAM H. FRICK, OF PHILADELPHIA, PENNSYLVANIA, ASSIGNOR OF ONE-HALF TO
SAMUEL E. FRICK, OF PHILADELPHIA, PENNSYLVANIA.

REAMER.

1,233,044.

Specification of Letters Patent. Patented July 10, 1917.

Application filed December 7, 1915. Serial No. 65,607.

To all whom it may concern:

Be it known that I, WILLIAM H. FRICK, a citizen of the United States, residing at Philadelphia, in the county of Philadelphia and State of Pennsylvania, have invented 5 new and useful Improvements in Reamers, of which the following is a specification.

This invention relates to machinists' tools and has particular reference to devices employed for truing and enlarging holes, commonly known as reamers.

The chief object of the improvements which form the subject matter of this application are:—to provide a practical tool of the character stated in which the cutters are separate members and so arranged that their edges will be uniformly and simultaneously adjusted relatively to the axis of the device; to furnish convenient and efficient 10 means for clamping the cutters in position when adjusted, and to produce a reamer of the design specified in which provision is made for the ready removal of the cutters thereof for purposes of sharpening or re- 15 pairing the same.

Further objects of this invention stated in detail may be mentioned as follows:—to provide a dirt proof casing for the working parts, thus adding to the durability of the 20 device; to furnish ample clearance for the chips; to provide cutters of maximum strength and designed to retain their edges for relatively long periods; and, incidentally thereto, provide fixed joints as a basis from 25 which to index in the process of sharpening or milling the cutting element.

The above, and other results of minor importance, are accomplished by means of the appliance illustrated in the accompanying 30 drawings forming a part of this application.

The apparatus, described in a general way, consists of a base or holder adapted to coöperate with a mandrel, a series of removable cylindrical cutting elements arranged 35 concentric to the axis of the tool, and mechanical movements designed to rotate the cutting elements for purposes of adjustment and to clamp the working parts in adjusted positions.

In the further disclosure of the invention, 40 reference is to be had to the accompanying drawings, in which similar characters of reference denote corresponding parts in the several views thereof, and in which:—

Figure 1 is a diametrical vertical sectional

view taken through the tool comprising the present invention,

Fig. 2 is a side elevation thereof;

Fig. 3 is a horizontal sectional view on the line 3—3 of Fig. 2;

Fig. 4 is a similar view taken on the line 4—4 of Fig. 2;

Fig. 5 is a plan view of the ring element;

Fig. 6 is a bottom plan view of the tool; and

Fig. 7 is a perspective view of one of the cutting elements or bits.

Referring more particularly to the accompanying drawings, the preferred form of the invention comprises a body or bit holder 70 10, the same being substantially cylindrical in contour and formed with a central bore 11 extending completely therethrough. Arranged concentrically of the axial line of the holder are a series of channels or grooves 75 12, which are circular in form and have one side open to the periphery of the holder; said grooves extending the entire length of said holder.

Located within the grooves 12 are cylindrical cutting elements or bits 13, each having a suitable longitudinal channel 14 formed in one side thereof, and so designed as to leave a salient lip 15 which forms the cutting edge of the bit. These lips or cutting edges 15, as will be noted, normally extend slightly beyond the outer circumference of the holder 10, in order that plenty of clearance will be had to permit the cutters to accomplish their several functions; furthermore, the circular formation of the cutters permits of a relatively long usage, a feature not found in the beveled cutter now in common use for the purpose of reaming. The cutters or bits are also capable of adjustment, so that their cutting lips 15 may be extended to different positions relative to the periphery of the holder 10, to produce openings of various calibers.

In order to regulate the cutting adjustments of the bits 13, the same are provided on one end with gear teeth 16 which latter extend into an annular chamber 17 formed in the body or holder 10. Positioned within the chamber 17 is a gear or pinion 18, the teeth thereof meshing with the teeth 16 of the bits 13. It will be evident that upon revolving the gear 18 the bits 13 will be forced to revolve simultaneously therewith, resulting in the equal adjustment of cut- 100 105 110

ting lips 15. The gear 18 is formed with an elongated hub or sleeve 19, provided with a central bore 20 which is concentric with the bore 11 of the holder 10. Surrounding the hub 19 is a bit actuating ring 21 and a locking member 22; the latter being provided with a circular opening 23 to receive the holder 10, and an enlarged head 24 of substantially the same diameter as the holder 10.

10 Set screws 25 are positioned within openings 26 formed in the head 24, and said screws extend upwardly through curved slots 27 provided in the ring 21 and are threaded into openings 28 formed centrally 15 in the lower portions of the bits 13. By this construction the screws 25, when tightened, secure the bits 13 and coöperating parts in such close frictional contact that the bits will be effectively locked against movement. The ring 21 is suitably keyed to the hub 19 of the gear 18 so that upon the rotation of said ring, the gears will be similarly revolved resulting in the adjustment of the bits 13. The curved slots 27 permit the ring 21 to be sufficiently rotated to actuate the gear 18.

The reamer thus described, when in actual use is attached to a lathe or other machine in the same manner as tools of ordinary 30 form by the engagement of a mandrel within the bores 11 and 20 of the tool. Slots 28 are formed in the hub and locking member so that the same may coöperate with a pin on the mandrel (not shown), thereby permitting a positive rotary movement to be imparted to said tool. The method of operating the mechanism consists merely in loosening the screws 25 so as to permit the ring 21 to revolve; this can be accomplished 35 by inserting a suitable form of tool into openings 29 formed in said ring. The movement of ring may then be performed so as to give the desired adjustment to the cutting lips 15. The screws are then tightened 40 and the device is ready for operation.

Having thus described the invention, I claim:—

1. In a reamer, the combination with a holder, and cutting elements rotatably 50 mounted therein, of gear teeth upon the cutting elements, a gear mounted upon the holder and meshing with said teeth, whereby said cutting elements may be adjusted, and means for locking the parts in adjusted 55 position.

2. In a reamer, the combination with a holder provided with recesses, of cylindrical cutters rotatably mounted in said recesses, said cutters being provided with gear teeth, 60 a gear rotatably mounted upon the holder and meshing with said teeth, means for rotating said gear, and means for simultaneously clamping the aforesaid means in adjusted position.

3. In a reamer, the combination with a

holder, of cutters rotatably mounted thereon and provided with gear teeth, a gear member rotatably mounted upon the holder and meshing with said gear teeth, means for actuating said gear member, a clamping element, and connections between said clamping element and the cutters for clamping the parts together, said connections being in loose engagement with the actuating means to permit rotation thereof when the clamp- 15 ing means is free for adjustment.

4. In a reamer, the combination of a holder having longitudinally extending recesses, cutters rotatably mounted in said recesses and provided with gear teeth, an annular gear rotatably mounted on the holder and in meshing engagement with said gear teeth, means upon the holder for holding said gear from longitudinal movement in one direction, an actuating ring connected 35 with the gear, a locking member fixed to the holder and arranged to hold the gear from longitudinal movement in the opposite direction, and clamping screws in threaded engagement with the cutters, and extending 40 through the actuating ring and locking member, said screws being adjustable to clamp and release the parts and being in loose engagement with the actuating ring to permit independent rotation of the latter 45 when released.

5. In a reamer, the combination of a hollow holder provided with recesses, cylindrical cutters rotatably seated in said recesses and provided with teeth, a gear engaging said teeth, means associated with said holder for locking said gear, and means for retaining said cutters in their seats.

6. In a reamer, the combination of a holder, cutting bits mounted upon the holder 105 for rotation upon their axes to advance or retract the cutting portions thereof, said bits having their cutting edges formed by grooves therein, and means for simultaneously rotating said cutting bits, the engagement of said means with said cutting bits 110 being independent of said grooves.

7. In a reamer, the combination with a holder, cutting elements rotatably mounted in the holder, of a gear for simultaneously 115 rotating said cutting elements, and means for locking said gear against rotation.

8. In a reamer, the combination of a holder, cutting elements rotatably mounted upon the holder, means revolvably mounted upon the holder for rotatably adjusting the cutting elements, and means upon the holder and engaging said revoluble means and cutters for clamping said parts in adjusted position, said means having a released position permitting revoluble motion of the said revoluble means and rotary motion of the cut- 125 ters.

9. In a reamer, the combination of a 130

holder having peripheral seats or recesses, cutters revolvably mounted therein, a gear revolvably mounted on the holder and meshing with the cutters for simultaneously adjusting the same, and means for engaging and holding the cutters against longitudinal displacement, and for clamping the cutters and gear in adjusted position, said means being operative to free the gear and cutters for turning motions.

10. In a reamer, the combination of a holder having peripheral recesses, cutting elements rotatably mounted in said recesses and provided with gear teeth, a gear rotatably mounted upon the holder and meshing

with said gear teeth, said gear having elongated slots therein, and fastening elements extending through said slots and engaging the cutting elements to retain the same in position, said fastening elements being adjustable to positions for respectively locking the gear and cutting elements against rotation and for freeing the same for rotation.

11. In a reamer, the combination with a holder, of cutting elements rotatably mounted in the holder, a rotatable gear for rotating said cutting elements, and means for locking the gear to the holder.

In testimony whereof I affix my signature.

WILLIAM H. FRICK.
